UNITED STATES PATENT OFFICE.

GEORGE H. GILMAN, OF BELMONT, MASSACHUSETTS.

HEAT-TREATING MACHINE.

Application filed July 18, 1921. Serial No. 485,708.

My invention relates to heat treating machines and particularly but not exclusively to one for heat treating drill steels.

The invention will be best understood from the following description when read in the light of the accompanying drawings of a specific embodiment of the invention selected for illustrative purposes, while the scope of the invention will be more particularly pointed out in the appended claims.

In the drawings:

- Fig. 1 is a plan with parts in section of a machine constructed according to the invention;
  - Fig. 2 is a development on the line 2—2 of Fig. 1;
  - Fig. 3 is a plan of Fig. 2;
  - Fig. 4 is a section on the line 4—4 of Fig. 3.
  - Fig. 5 is a view looking at the lowermost portion of the left leg of the carrier in Fig. 4 from the right;
  - Fig. 6 is a view looking at the lowermost portion of the left leg of the carrier in Fig. 4 from the left when the carrier is at the loading table, and with associated parts shown diagrammatically in dotted lines;
  - Fig. 7 shows a detail of the machine on an enlarged scale;
  - Fig. 8 is a section on the line 8—8 of Fig. 7;
  - Figs. 9 and 10 show details of the machine on an enlarged scale;
  - Fig. 11 is a section on the line 11—11 of Fig. 3;
  - Fig. 12 is a plan view of the furnace with the top removed;
  - Fig. 13 is a development on the line 13—13 of Fig. 12;
  - Fig. 14 is a section on the line 14—14 of Fig. 12; and
  - Fig. 15 is a perspective of a portion of the furnace resistance and some of its associated parts in assembled relation.
- Referring to the drawings, I have shown a closed cylindrical plate 1, mounted in elevated position in any suitable manner, as for example, by means of legs 3 supported on the base-plate (not shown) of the machine. Distributed around the plate I have shown a loading table 5, a furnace 7, a quenching tank 9 and a disengaging mechanism 11, illustrative examples of all of which parts will hereinafter be more particularly described. The upper and lower edges of

the plate 1 affords tracks for the wheels 13 for the carriers for conveying the drill steels a. Each carrier as illustrated comprises legs 15 and 17 connected at their upper ends by a cross piece 18, the U-shaped member thus formed straddling the track, and the wheels 13 being pivotally secured to the leg 17.

For yieldingly gripping the drill steels to the carrier I have shown integrally formed with the upper and intermediate portions of the leg 15 the projections 19, and facing the projections clips 21 pivoted to the pin 23 carried by the leg and biased toward the projections 19 by the springs 25.

For locking the drill steels to the carrier I have shown the lowermost portion of the leg 15 formed with a projection 27 forming one jaw of a gripping means, the other jaw of which is provided by the member 29 integrally formed with the end of the rock shaft 31 pivoted to the leg. For moving the jaw 29 I have shown the cam member 33 slidably mounted on the leg and having the oppositely inclined cam surfaces 35 and 37 cooperating with the ends of the lever 39 formed integrally with the end of the rock shaft 31 opposite the jaw 29. Secured to the cam member 33 is a push rod 41 sliding in ears 43 carried by the leg. Surrounding the rod is a compression spring 45 for normally biasing the cam member to move the jaw 29 toward the jaw 27, the push rod for this purpose being provided with a collar 47 serving as one abutment for the compression spring, and the other abutment for the compression spring being provided by the upper ear 43.

The drill steel is placed on the carrier as the latter passes the loading table, the table acting to gauge the position of the steel on the carrier. When this is to be done the operator places the end of the drill steel to be heat treated on the loading table and keeping such end in contact with the surface of the table slides the drill steel against the carrier to force it between the projections 19 and clips 21. As herein shown, for the first part of its travel over the loading table the locking means afforded by the jaws 27 and 29 is open, but before the carrier reaches the end of the loading table the locking means closes and remains closed until just before the carrier, after travelling around the track, again reaches the loading table.

The drill steel is placed on the carrier as the latter passes the loading table, the table acting to gauge the position of the steel on the carrier. When this is to be done the operator places the end of the drill steel to be heat treated on the loading table and keeping such end in contact with the surface of the table slides the drill steel against the carrier to force it between the projections 19 and clips 21. As herein shown, for the first part of its travel over the loading table the locking means afforded by the jaws 27 and 29 is open, but before the carrier reaches the end of the loading table the locking means closes and remains closed until just before the carrier, after travelling around the track, again reaches the loading table.

For operating the locking means the loading table is provided with an upstanding flange 49 having a continuation 50, the upper edges 51 and 53 of the flange and its continuation being in the path of the cam member 33 on the carrier and engaging the cam member for a portion of the travel of the carrier around the track. As the carrier approaches the loading table the cam member 33 engages the lower end of the edge 53 of the continuation 50 to force the cam member upward and cause the drill steel to be disengaged. The operating edge 51 of the flange 49 terminates before the end of the loading table is reached in order that before the carrier moves away from the loading table the cam member will be suddenly released to cause the spring 45 to forcibly drive the jaw 29 against the drill steel. For absorbing the shock to the parts occasioned by release of the cam member 33 when a drill steel is not inserted I have shown a buffer for the movable parts. This buffer may be of any suitable construction, and as shown, for this purpose the flange 49 is formed with a cut-away portion providing a lower edge 55 and adapted to be engaged by the lower end of the cam member 33 on excess movement of the latter. In Fig. 6 I have represented diagrammatically by dotted lines the relative positions of the end of the continuation 50 of the flange 49 and the cam member 33, the continuation 50 of course being shown out of position in this figure, its actual position being indicated in Figs. 1 and 2.

The disengaging mechanism for removing the drill steels from the carriers heretofore referred to herein comprises a standard 57 which carries the hooked-shaped arms 59. As the carrier approaches the loading table the ends of the arms 59 enter the space between the drill steel and the leg 15 of the carrier in order that continued movement of the carrier will force the drill steel from between the projections 19 and clips 21. The continuation 51 of the flange 49 of the loading table conveniently is so positioned as to cause release of the lower end of the drill steel immediately after the arms 59 have pulled the drill steel from between the projections 19 and clips 21.

For causing the carrier to move along the track I have shown inside the plate 1 a turret 61 supported on a centrally located shaft 63 and rotated by any suitable power means. Projecting radially from the turret are the four propeller heads 65 adapted to engage the side of the leg 17 of the carrier and push the latter. Each propeller head is mounted on a plunger 67 slidably mounted in the turret and carrying a roller 69 held in engagement with the stationary cam track 71 by means of a compression spring 73. The cam track is so formed that

the propeller is moved out of engagement with the carrier after the latter has been added to the row standing on the track above the furnace and said row has been pushed forward a distance equal to the width 70 of a carrier. The cam track does not permit reengagement with a carrier until the propeller head reaches the last carrier of the row above the furnace, this reengagement occurring just prior to the addition of the 75 new carrier and the pushing forward of the row.

When the carrier leaves the loading table it moves down the inclined track 74 afforded by the edges of the plate 1 and lowers the 80 end of the drill steel into the furnace. The furnace illustrated is of the electric resistance type. It comprises a metal casing 75, open at the top and having the side walls 77 concentric with the plate 1, and the radial 85 end walls 79 and 81. The casing is provided with a removable cover 83 of fire-clay brick, tile, or other suitable refractory material, and below the cover is arranged similar material, forming the side walls 85 90 and bottom walls 87, to constitute a channel-shaped passage 89. The cover is formed with a slot 91 through which the drill steel may be inserted in order that its end may project into the passage 89 and be heated. 95 For generating the heat in the passage 89 are placed a series of U-shaped resistance elements, each element comprising the flat bar of resistance material affording the side members 93 and 95 and bottom member 97. 100 Referring to Fig. 15, for any given U-shaped element, the upper end of the side member 93 is connected to the upper end of the side member 93 at the right of it while the side member 95 of said element is connected to the upper end of the side member 95 at the left of it. In this way the U-shaped elements are connected in series.

The connected U-shaped members may be formed as an integral casting, and instead of the casting extending the entire length of the channel 89 I may form the same in sections. For this purpose I have shown in my present embodiment each section as comprising four U-shaped members having terminals 99 and those of adjacent sections being welded or otherwise secured in electrical contact to blocks 101. Preferably, the terminal strips and blocks 101 are of greater conductivity than the other portions of the 110 resistance in order to confine the heat generated to the channel 89, and for this purpose the U-shaped members may be formed of a known chromium-nickel alloy and the terminal strips and blocks of nickel welded to, 115 the U-shaped members, such weld being indicated at 103. The terminal strips rest on top of the material forming one of the side walls of the channel 89, between the same and the cover. The bottom of the U-shaped 120 125 130

members are supported on the raised bosses 105 carried by the bottom walls of the channel. For insulating the terminal strips I have shown blocks 107 of porcelain or other suitable material, and to the blocks 101 carried by the terminals 99 of the two end U-shaped members I connect the conductors 109 for impressing on the furnace a regulatable source of electro-motive force.

10 For measuring the temperature of the furnace and thereby enabling the operator intelligently to control the temperature I have shown inserted through the wall of the furnace at one end thereof the terminal 15 portion of the thermo-electric couple 111 or other pyrometer, the same extending into the channel 89 between the last two U-shaped resistance elements.

Herein the end wall 81 of the furnace 20 carries a door 113 normally biased by any suitable means to closed position, which door when struck by the drill steel or its carrier moving toward the end of the channel will 25 open the door and permit the drill steel to leave the furnace.

When the carrier is pushed to cause the drill steel to move out of the furnace it moves on the downwardly inclined track 115 provided by the plate 1 and runs ahead 30 of the propeller head to the bottom of the incline where it remains stationary until the propeller again catches up with it to cause further movement. When the drill steel is standing stationary in the position 35 just referred to, its end is submerged in the quenching liquid of the quenching tank 9, the level of which liquid is indicated at 117. The quenching tank is provided with an inlet 119 and an outlet 121, the latter being 40 in the form of a pipe having the screw-threaded end 123 carrying a sleeve 125 which may be turned to cause its upper edge to be elevated more or less above the bottom of the tank and thus regulate the level 45 of the quenching liquid. The inlet 119 is shown as provided with a funnel-shaped end 127, the upper portion of which is covered with a partition 129 having formed therein a plurality of small perforations 50 permitting the escape of the quenching fluid, and for this purpose I have indicated the partition as being formed of fine mesh wire-gauze. By this means the discharge 55 from the pipe 119 is diffused and forms a zone of cold quenching liquid which hardens the cutting and reaming edges of the bit.

After the propeller again moves into contact with the carrier standing over the inlet 119 of the quenching tank it moves the carrier along the downwardly inclined track 131 afforded by the edges of the plate 1 above the quenching tank and this causes the end of the drill steel gradually to be lowered into the quenching liquid to quench

the remaining heated portion thereof and in this way to secure a tough backing for the cutting and reaming edges hardened as heretofore described.

When the carrier reaches the end of the 70 downwardly inclined portion 131, it is moved up the upwardly inclined portion 133 to lift the drill steel out of the quenching tank, and after the steel is disengaged from the carrier the latter moves to the 75 loading table where a new steel may be placed on the carrier as heretofore described.

On the inclined portions 74, 115 and 133 of the track I may provide guard rails 135, one of which is illustrated in Figs. 7 and 8. 80 As shown these guard rails are provided with flanges 137 secured by means of bolts 139 to the plate 1. The guard rail above the inclined track 115 at its upper end is pivoted to swing about the uppermost bolt 85 139, and to permit this the bolt holes 141 for the lower bolts 139 are in the form of slots concentric with the uppermost bolt. The guard rail is normally biased by resilient means hereinafter described to move 90 toward the track so that the space between the track 115 and that afforded by the guard rail is less than the diameter of the wheels 13, and by this means the guard rail acts 95 to check the speed of the carrier as it moves down the track.

Above the track 131, to prevent the carrier from moving ahead of the propeller head, I have shown a rail in the form of a bar 143 which is supported on bolts 145 100 each secured thereto at one end in offset relation to the bar and mounted in brackets 147 supported on the plate 1. The bar is resiliently held in spaced relation to the track 131 by means of compression springs 105 149 in order that the space normally existing between the guard rail and the track will be less than the diameter of the wheels 13. The springs 149 surround the bolts 145, and abut at one of their ends the 110 flanges 151 formed as part of the brackets 147 and serving to guide the bolts, and at their other ends abut the nuts 153 carried by intermediate portions of the bolts. Near their lower ends the bolts 145 carry 115 stops in the form of nuts 155 adapted normally to rest against the lower flanges 157 formed as part of the brackets 147 and serving to guide the lower end portions of the bolts. By means of the nuts 120 155 the space between the track and the bar may be adjusted. The end of the bar adjacent the track 115 is enlarged to form a shoulder 159, positioned to be struck by the wheel 13 when the carrier reaches the 125 bottom of the incline in order to bring the carrier to rest, the parts being so constructed that when the propeller reengages the carrier the force exerted by the propeller is sufficient to raise the bar 143 to permit 130

the wheel to move under the enlargement. The end portion of the bar is provided with a projection 161 which rests on the top of the guard rail 135 to cause it to be resiliently pressed toward the track 115 as hereinbefore described.

To prevent swinging of the carrier, when the wheel 13 is against the shoulder 159, and thereby to prevent movement of the drill steel from above the inlet 119 of the water tank, I have shown secured to the plate 1 a spring pawl 163 which engages the left hand side of the leg 17 of the carrier as viewed in Fig. 2 when the same is over the inlet 15 of the water tank as illustrated by Figs. 2, 3 and 4. It will be understood that the flexibility of the member 163 permits the carrier to pass by it as the carrier moves into the position just referred to.

To prevent the carrier from moving ahead of the propeller when the carrier is over the loading table I have shown secured to the inside of the plate 1 at the loading table the ends of a flexible bow-shaped strip 165 which carries the flexible bow-shaped arms 167 also secured at their ends to the plate. The strip 165 by these means is resiliently held away from the track a distance slightly greater than the space normally existing between the plate 1 and the adjacent edge of the leg 17 of the carrier and acts as a friction brake for the carrier when the same moves over the loading table.

To prevent excess movement of the row 35 of drill steels above the furnace I have shown secured to the inner side of the plate 1 a flexible member 169 which has the rounded end portion 171 adapted to snap between the legs 17 and the last two carriers of the row. The member 169 is of strength sufficient to prevent accidental movement of the row and to yield when the row is pushed by the propeller head toward the end of the furnace. It also insures that if, owing to tilting of the next to the last carrier of the row, said carrier should be struck by the propeller as it moves toward engaging position with the last carrier of the row, said next to the last 50 carrier will not be moved out of the furnace prematurely.

It will be understood that I have described one specific embodiment of my invention for purposes of illustration and that wide deviations may be made therefrom without departing from the spirit of my invention.

Claims:

1. In an electric heat treating machine, 60 means providing a row of U-shaped resistance elements, and automatic means for moving a bit portion of a drill steel or the like through the space between the sides of said elements.

2. In an electric heat treating machine,

means for moving drill steels or the like laterally along a path, resistance conductors arranged at the sides of said path opposite each side of the end portion of said drill steel and opposite the extreme end of 70 said portion.

3. In an electric heat treating machine, means for moving a drill steel or the like along an arcuate path, and means providing a series of U-shaped resistance elements 75 arranged to embrace the bit end only of said steel.

4. In an electric heat treating machine for drill steels, means providing side and bottom walls arranged to form an arcuate 80 chamber, resistance coils adjacent said side and bottom walls, and means for moving the bit ends only of the drill steels to be heated through said chamber.

5. In a heat treating machine for drill 85 steels, means for conveying drill steels along a path, electric resistance elements arranged at the side of said path for imparting radiant heat to the ends of said drill steels, a tank for quenching liquid in said path, and means for moving the ends of said drill steels through said quenching liquid after they are heated by said resistance elements.

6. In a heat treating machine, means for 95 conveying drill steels in a vertical position along a path, electric resistance elements arranged at the sides of said path for imparting radiant heat to the ends of said drill steels, a tank for quenching liquid in said path, and means for moving the ends of said drill steels through said quenching liquid after they are heated by said resistance elements.

7. In a heat treating machine, means for 105 conveying drill steels along a path, spaced walls of refractory material at the sides of said path at the ends only of said drill steels, electric resistance elements lining said walls, a tank for quenching liquid in 110 said path, and means for moving the ends of said drill steels through said liquid after they are heated.

8. A heat treating machine for drill steels having, in combination, a heater comprising 115 electric heating elements, a cooler, and drill-steel-end-presenting-means movable successively to present the ends of drill steels to said heater and cooler.

9. A heat treating machine for drill steels 120 having, in combination, a heater comprising electric heating elements, a cooler, and means for successively presenting the end only of each of a group of drill steels to said heater and cooler, said means maintaining the end 125 of each drill steel in the presence of said heater for the same length of time.

10. A heat treating machine for drill steels having, in combination, a furnace having 130 electric heating elements, and drill-steel-end-

presenting-means for presenting the ends only of drill steels to said furnace and removing them therefrom.

11. A heat treating machine for drill steels having, in combination, a heater, a cooler, drill-steel-end-presenting-means for successively presenting the ends only of drill steels to said heater and cooler, said presenting means being movable for moving said steels laterally along a path through said heater, said heater having electric resistance elements at opposite sides of said path and opposite the ends of the drill steels traversing said path.
15. 12. A heat treating machine for drill steels having, in combination, a heater, a cooler, drill-steel-end-presenting-means for successively presenting the ends only of drill steels to said heater and cooler, said presenting means being movable for moving said steels laterally along a path through said heater, said heater having electric resistance elements and refractory walls heated by said heating elements at opposite sides of said path and opposite the ends of the drill steels traversing said path.

13. A heat treating machine for drill steels having, in combination, a heater, a cooler comprising a quenching liquid, drill-steel-end-presenting-means for successively presenting the ends only of drill steels to said heater and cooler, said presenting means being movable for moving said steels laterally along a path through said heater and then substantially abruptly to place the tips of the heated portions of said ends in said liquid and thereafter gradually to lower said heated portions into said liquid, and said heater having at opposite sides of said path and opposite the ends of said steels traversing said path electric heating elements and walls of refractory material.

14. In a heat treating machine, a tank for quenching liquid, means for plunging the ends of previously heated drill steels into said liquid, an inlet for said tank, and means affording an adjustable overflow for said tank.

15. In a heat treating machine, a carrier for drill steels, a tank for quenching liquid, means for gauging the position of said steels on said carrier, an inlet for said tank, and an adjustable overflow therefor.

16. In a heat treating machine, a quenching tank, an inlet for said tank, said inlet

having a plurality of small discharge orifices, and means for moving the end of a previously heated drill steel into proximity with said orifices, and for then holding said end stationary, whereby said end is subjected to the discharge from said orifices.

17. In a heat treating machine, a quenching tank, an inlet for said tank, said inlet having a plurality of small discharge orifices, means for moving the end of a previously heated drill steel into proximity with said orifices and for then holding said end stationary, whereby said end is subjected to the discharge from said orifices, and means for maintaining the level of quenching liquid in said tank above said orifices.

18. A heat treating machine having, in combination, a heater, a quenching tank having an upwardly directed inlet and an outlet for quenching liquid, drill-steel-end-presenting-means for successively presenting the ends only of drill steels to said heater and cooler, said presenting means being movable to cause said drill steels substantially abruptly to be removed from said heater and to be placed vertically with the tips of their heated ends in said quenching liquid above said inlet, said inlet having means diffusing the discharge of liquid therefrom, and said presenting means allowing said steels to remain stationary above said inlet until said tips are hardened and then gradually to lower said ends into said liquid.

19. A heat treating machine having, in combination, a heater, a quenching tank having an upwardly directed inlet and an outlet for quenching liquid, drill-steel-end-presenting-means for successively presenting the ends only of drill steels to said heater and cooler, said presenting means being movable to cause said drill steels substantially abruptly to be removed from said heater and to be placed vertically with the tips of their heated ends in said quenching liquid above said inlet, said inlet having means diffusing the discharge of liquid therefrom, and said presenting means allowing said steels to remain stationary above said inlet until said tips are hardened and then gradually to lower said ends into said liquid while moving said steels laterally.

In testimony whereof, I have signed my name to this specification.

GEORGE H. GILMAN.
